UNITED STATES PATENT OFFICE.

FREDERICK J. MEERLENDER, OF NEWARK, NEW JERSEY.

CUFF BUTTON OR FASTENER.

SPECIFICATION forming part of Letters Patent No. 731,930, dated June 23, 1903.
Application filed May 8, 1902. Serial No. 106,443. (No model.)*To all whom it may concern:*

Be it known that I, FREDERICK J. MEERLENDER, a citizen of the United States, residing at Newark, in the county of Essex and State of New Jersey, have invented certain new and useful Improvements in Cuff Buttons or Fasteners; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to buttons for that class of cuffs commonly called "link-cuffs," and in which the inner faces of the two ends of the cuff are pressed more or less completely flatwise together, said ends pointing in the same direction, so that a V-shaped connection is formed. A cuff button or fastener is then provided, having a V-shaped body to exteriorly straddle the joined edges of the cuff and projections at the inner sides of said body portion to enter the buttonholes of the cuff; and the specific objects of the present invention are to secure in such a button rigidity and firmness, to increase the stability of the button upon the cuff, to provide an improved construction of the projections for entering the buttonholes, and to secure other advantages and results, some of which may be referred to hereinafter in connection with the description of the working parts.

The invention consists in the improved cuff button or fastener and in the arrangements and combinations of parts of the same, all substantially as will be hereinafter set forth and finally embraced in the clauses of the claim.

Referring to the accompanying drawings, in which like letters of reference indicate corresponding parts in each of the figures, Figure 1 shows a cuff provided with a button of my improved construction. Fig. 2 is a section transversely of the cuff, as on line *x*, Fig. 1. Fig. 3 is a section longitudinally of the cuff, as on line *y*, Fig. 2; and Fig. 4 is a perspective view of the button detached from the cuff.

In said drawings, *a* indicates a cuff to which my improved button or fastener is shown ap-

plied. Said button comprises a body portion *b*, which is non-elastic and either cast or stamped out of a single piece of metal into a V shape to fit over the cuff edges, as shown in Figs. 1 and 2. Said body portion is of sufficient strength to resist the normal strain of use, and thus provides two arms *c c*, which are in rigid or fixed relative position. To secure a maximum rigidity, each arm *c* is widened laterally at its base or at the joining *d* of the two arms and tapers in width from thence toward its extremity, whereby great firmness and strength at said extremity are obtained. Each arm *c* is at the inner face of its extremity provided with means for entering through the buttonhole of the cuff, said means comprising a post *e*, carrying at its outer end a head *f* and being either integral with the arm *c* or fastened thereon by soldering, brazing, or any other means adapted to secure a rigid connection. The post *e* is flattened or compressed from two opposite sides, so as to give it a narrow oblong cross-sectional shape, and is thus adapted to fit nicely in a buttonhole. The head *f* is of rounded form, adapted to be pushed through a buttonhole without great difficulty and at the same time resist withdrawal. Preferably said head is ellipsoidal in shape, as shown, with rounded ends, and is secured to the end of the post *e* at its side and adjacent to one end, the elongated head thus lying in the plane of the elongated diameter of the flattened post and projecting from the edge of said post next to the extremity of the arm *c*. A very ready insertion of the head into a cuff is thus secured and a good holding effect. The widening of the arms *c c* at their union provides a long straight bearing of the cuff-button against the edges of the cuff and serves to prevent any appreciable rocking or swinging of the button upon its posts *c* when worn. In this connection it should be noted that the ends of the heads *f*, being flush with the inner edges of the posts *e*, permit the same to enter the buttonhole close to its outer end, and thus avoid any dropping away of the button from the cuff edges after the post has been seated a little time and adjusted itself. Furthermore, I prefer to set the posts *e* with their elongated diameters somewhat oblique

with respect to the arms *c c*, as shown in Figs. 3 and 4 more particularly, and the button is then designed to be applied to the cuff with the edges of the post next the extremities of the arms directed toward the outer end of the cuff or end which is exposed in wearing. The flattened posts then tend to adjust themselves longitudinally of the buttonholes, and this presses the body or clasping portion of the button firmly against the cuff edges at its edge next the outer end of the cuff. The heads *f* are then preferably set obliquely with respect to the longest diameter of the posts, so that they lie to a greater or less extent crosswise of the buttonhole and hold better, as shown in Figs. 3 and 4.

It will be understood that it is the purpose of my invention to secure a cuff-button of perfectly rigid construction, depending upon the resiliency of the starched cuff and the proper fit of the button to secure a correct effect. The heads *f* are therefore rounded smoothly, so that they present outer surfaces which have a smooth continuous curvature, and hence are adapted to pass through the buttonholes with minimum effort. This is indispensable to my rigid construction of body portion, since the arms being unyielding there is little room for manipulation in buttoning the cuff and the heads can only be pushed straight into the buttonholes without any twisting or tipping.

Having thus described the invention, what I claim as new is—

35 1. The herein-described one-piece cuff-button, comprising a rigid V-shaped body portion adapted to receive between its arms the edges of a cuff, and having at the inner faces of the ends of said arms posts with laterally-projecting heads at the extremities thereof, said posts and heads being of one piece, or

integral, with the body, and being adapted to enter the buttonholes of the cuff.

2. A cuff-button having a V-shaped body portion adapted to clasp the edges of a cuff, 45 posts at the ends of the inner facing sides of the arms, each having a side flattened obliquely to the length of the arm on which it stands, and ellipsoidal heads on said posts.

3. A cuff-button comprising a V-shaped 50 body adapted to clasp the edges of a cuff, posts fixed to the inner facing sides of the arms of said body, each post being flattened from opposite sides and arranged with its longest diameter oblique to the length of the 55 arm on which it stands, and heads on said posts.

4. A cuff-button comprising a rigid V-shaped body adapted to clasp between its 60 arms the edges of a cuff, flattened posts fixed at the inner facing sides of said arms, and ellipsoidal heads fixed on said posts, each with its major axis at an angle to the plane of flattening of the post.

5. A cuff-button comprising a V-shaped 65 body adapted to clasp between its arms the edges of a cuff, flattened posts on the inner facing sides of said arms, adapted to lie in the buttonholes of the cuff, and elongated heads arranged on such posts, each head being disposed obliquely to the direction of the flattening of the post and having its end next the bend of the body portion substantially flush with the post.

In testimony that I claim the foregoing I have hereunto set my hand this 3rd day of May, 1902.

FREDERICK J. MEERLENDER.
